UNITED STATES PATENT OFFICE.

CHARLES OSTEN, OF NEW HAVEN, CONNECTICUT.

COMBINED BUTTON AND BELT-LOOP.

1,313,640.

Specification of Letters Patent.

Patented Aug. 19, 1919.

Application filed August 26, 1918. Serial No. 251,434.

To all whom it may concern:

Be it known that I, CHARLES OSTEN, a citizen of the United States, residing at New Haven, in the county of New Haven 5 and State of Connecticut, have invented a new and useful Improvement in Combined Buttons and Belt-Loops, and do hereby declare the following, when taken in connection with the accompanying drawings and 10 the characters of reference marked thereon, to be a full, clear, and exact description of the same, and which said drawings constitute part of this application and represent, in—

Figure 1, an outside face view of the device shown as applied to a waist-band.

Fig. 2, an inside face view of the same.

Fig. 3, a perspective view of the device detached.

Fig. 4, a plan view of the blank from 20 which the device is formed.

Fig. 5, inside face view illustrating a modified form of my invention.

Fig. 6, side view of the same detached.

This invention relates to an improvement 25 in combined buttons and belt-loops, particularly adapted for the waist-band of trousers. The object of the invention is to simplify the production and mode of application, and the invention consists in the construction 30 hereinafter described and particularly recited in the claim.

In carrying out my invention I form a disk 7 at one end 15 of a strip 8, as shown in Fig. 4. The disk is then struck up to 35 form a flat button 9 like the common suspender button and the strip is folded to form a rectangular loop 10 comprising a front plate and a back plate formed by the ends 11 and 15 of the strip. The loop is 40 placed over the upper edge of the waistband so that the button stands inside of the band

and a belt loop is provided outside the band. The lower end 11 of the strip is passed through the fabric and may be secured by sewing through holes 12 or the end of the strip may be formed with inwardly struck 45 prongs 13 as shown in Figs. 5 and 6, which may be bent to hold the device in place. The button will be pierced as at 14 so that it may be sewed to the waist band and in 50 some cases—this sewing through the button may be all that is necessary to secure the device in place. If desired the upper end of the button-end 15 may be pierced as shown in Fig. 3, or formed with prongs 16, 55 as shown in Fig. 6 to permit of additional attachments, if necessary.

This device is readily formed and readily attached to a garment and forms in a single piece of metal a suspender button and a belt-loop. The surface of the device may be finished in color to harmonize with the color 60 of the garment to which it is applied, so that the loops will not be more conspicuous than are the fabric loops now more generally 65 used.

I claim:—

A combined button and belt loop formed from a single strip of metal folded to form 70 a rectangular loop comprising a front plate and a back plate formed by the ends of the strip, said plates connected at the top and bottom, one end of the strip terminating in a disk struck up to form a button.

In testimony whereof I have signed this 75 specification in the presence of two subscribing witnesses.

CHARLES OSTEN.

Witnesses:

FREDERIC C. EARLE,
J. HAROLD FLYNN.
